Primary Examiner — Cathron Brooks*Assistant Examiner* — Catherine Posthauer(74) *Attorney, Agent, or Firm* — Leanne Taveggia Farrell; Westman, Champlin & Koehler, P.A.(57) **CLAIM**

The ornamental design for a display unit, as shown and described.

DESCRIPTION

FIG. 1 is a perspective view of a display unit showing our new design;

FIG. 2 is a front view thereof, the opposing back view being identical;

FIG. 3 is a side view thereof, the opposing side view being identical; and,

FIG. 4 is a top view thereof.

The broken lines shown on the drawings, regardless of size or thickness, illustrate portions of the article that form no part of the claimed design.

1 Claim, 2 Drawing Sheets(56)
